V. W. JENSEN

AMPLIFIER

Filed March 3, 1924

INVENTOR

Vernon W. Jensen

Harry Bowen

ATTORNEY

UNITED STATES PATENT OFFICE.

VERNON W. JENSEN, OF SEATTLE, WASHINGTON.

AMPLIFIER.

Application filed March 3, 1924. Serial No. 696,434.

To all whom it may concern:

Be it known that I, VERNON W. JENSEN, a citizen of the United States, residing at Seattle, in the county of King and State of Washington, have invented a new and useful Amplifier; and I do hereby declare that the following is a full, clear, and exact specification, such as will enable others skilled in the art to which it appertains to make and use the same.

The invention is a collapsible fibre, bell section, that may be placed at the end of a horn or other device forming the small section of the tone chamber, for the production or reception of sound.

The object of the invention is to provide an amplifier that is collapsible.

Another object of the invention is to provide a collapsible amplifier that will improve rather than destroy or distort the sound waves.

And a further object of the invention is to provide a collapsible bell or amplifier that is of a simple and economical construction and that may readily be set up or taken down.

With these ends in view the invention embodies a section in the form of a frustum of a cone which is constructed of segments 30 hinged together and provided with a latch, and a horn shaped section over the end of which the former section may be placed.

Other features and advantages of the invention will be seen from the following description taken in connection with the drawings, wherein:

Figure 1 is a side view of the amplifier with part broken away.

Figure 2 is an end view of the bell shaped section.

Figure 3 is a detail showing the latch for holding the sections of the bell shaped section together.

Figure 4 is a detail showing the hinge for holding the sections of the bell shaped section together.

Figure 5 is a view showing a horn of an alternate design.

In the drawings I have shown my device 50 as it would appear wherein numeral 1 indicates the bell shaped section which is constructed of three sections 2, 3, and 4. The sections are held together by hinges 5, one member 6 of which is attached to one edge 55 of one of the sections 2, 3 or 4, and the other member 7 of which is attached to the adja-

cent section with a spacer 8 between it and section. The edge 9 of the section to which the member 7 of the hinge 5 is attached will project beyond the center of the hinge as 60 shown in Figures 2 and 4 so that the edge of the adjoining section which is attached to the opposite member 6 of the hinge will lap over it to form a seal joint. It is understood that any number of the hinges 5 may be used 65 or that one continuous hinge may be used, or that any other means may be used for connecting the segments together.

The two open edges of the segments are held together by a latch 10 as shown in 70 Figure 3. The latch 10 is held to the section 4 by rivets 11 and may be constructed of a flat piece of material with one edge 12 bent upward at right angles. This edge or projection may be placed through an 75 opening 13 in a strip of material 14 that is attached to the section 2 by rivets 15 with a spacer 16 between the strip 14 and the section 2. This will leave a space 17 between the edge of the section 2 and the strip 14 into which the edge of the section 4 may project when the sections are snapped together. Although I have shown a latch of this design it is understood that any suitable means may be used for holding the sections 80 together.

When the sections are held together as hereinbefore described they will form a frustum of a cone as shown and they may be placed over the end of the horn shaped 90 section 18 as shown in Figure 1. It will be seen that the end 19 of the horn shaped section will be provided with a ridge 20 at the ends and another ridge 21 a short distance 95 from the end which will leave a recess 22 around the end of the section between the ridges 20 and 21. The bell shaped section 1 may be placed in this recess or groove either by snapping it over the end or by placing the horn shaped section through it. 100

In Figure 5 I have shown a horn section 23 of an alternate design in which the large end is bent backward over the small end in order to economize space and the bell section 1 may be placed over the end 24 in the same manner as that shown and described for the end 19 of the section 18. It is also understood that this horn section may be made of any other suitable design or size. 110

In the design shown in Figure 1 I have shown a dotted line 25 across the horn section 18 to indicate that this section may be

made in two sections with one telescoping in the other, and it is also understood that this horn section may be made of any number of telescoping sections. In Figure 5 I have shown a dotted line 26 which will indicate that the horn section 18 or the bell section 1 may be made square instead of round as shown, and it is also understood that these sections may be made in any desired shape.

10 It is understood that other changes may be made in the construction without departing from the spirit of the invention. One of which changes may be in the material of which the sections are made as it is understood.

15 20 25

15 It is understood that the bell section 1 in particular may be made of any other suitable material instead of the fibre as specified; another change may be in the location of the joint between the horn section and the collapsible section as it is understood that the sections may be connected at any suitable point; and still another change may be in the means for holding the collapsible section to the horn section as it is understood that these may be connected by any suitable means.

The construction will be readily understood from the foregoing description. To use the device it may be assembled as shown and attached to either a phonograph or a 30 radio and it will be seen that by making the bell section of the tone chamber collapsible it will be possible to carry an unusually large tone chamber from one place to another. It will also be seen that with a 35 tone chamber of this type it will be possible to provide a small portable phonograph radio or other sound producing device with a large tone chamber.

Having thus fully described the invention, what I claim as new and desire to secure by Letters Patent, is:—

In an amplifier, a plurality of sections conforming to the shell of a frustum of a cone, said sections being hinged together 45 at their edges with the edge of one section extending beyond the center of the hinge to form a lap joint and one of said joints having the hinges omitted and being provided with a snap for holding the sections 50 together.

VERNON W. JENSEN.
